TANDEM CHUCK WIND-UP

Frank Scott Pollock, Jr., Martinsville, Va., assignor to E. I. du Pont de Nemours & Company, Wilmington, Del., a corporation of Delaware

Application February 17, 1948, Serial No. 8,789

10 Claims. (Cl. 242—35.5)

1

This invention relates to winding machines and more particularly to the winding of filamentous structures, such as a yarn or thread or any such continuous filament, by a method and with apparatus which are adapted to increase by a large amount the capacity of industrial plants such as textile plants.

By "filamentous structures" is meant monofilaments, yarns, threads, strands, cords, ropes, fibers and the like. Accordingly, the structure may be composed of a single filament or a plurality of filaments.

In conventional wind-up operations yarn or the like is taken from the supply source, such as a spinneret, and is passed through feed rolls onto a bobbin driven by surface contact with a revolving drive roll. The surface speed of the bobbin is the same as that of the driving roll. A single thread is wound in this way on the bobbin at a certain speed. A single traverse guide is used in the operation. In this method capacity per unit can be increased only by increasing wind-up speeds. While this method has been satisfactory, with increasing production it has become desirable to increase wind-up capacity further. This could easily be done by merely increasing the number of production units. In the interests of economy in equipment and space such a procedure is not commercially feasible. Similarly, wind-up units are normally run at optimum speeds and additional capacity cannot be obtained by increasing wind-up speeds without some sacrifice, such as a loss in yarn quality or an excessive increase in maintenance cost.

Accordingly, it is an object of this invention to provide a method whereby wind-up capacity may be greatly increased while employing substantially the same amount of equipment and space. It is a further object to provide a method for increasing the production capacity of each wind-up position. A still further object is the provision of apparatus for the winding of filamentous structures at greatly increased capacities to produce packages of high quality. These and other objects appear hereinafter.

These objects are accomplished by passing, as a unit, a plurality of filamentous structures, such as threads from a plurality of supply sources through a guide mechanism, such as a single traverse guide or a plurality of traverse guides appropriately placed, and then passing each structure to its respective wind-up core, such as a bobbin, spool, etc., each of which is surface driven by the same driving roller, ultimate separation of the structures occurring at the point of wind-

2

up of one of the structures. For example, two threads of a yarn are passed from a supply source through a single traverse guide as one thread of yarn and then into the nip formed by the first bobbin and the drive roller. The threads are then separated: one thread is passed through the nip to the top surface-driven bobbin and is wound thereon, and the other thread is passed between the top bobbin and the drive roller following the drive roll to a lower bobbin which is immediately below the upper bobbin and upon which the thread is wound. By this invention it is possible to cause a plurality of filamentous structures to follow a guide mechanism, running one structure underneath one or more wind-up cores and by so doing wind a plurality of acceptable yarn packages in each wind-up position without decreasing the quality of the filamentous structures.

20 The invention will be more clearly understood by reference to the following figures which illustrate one of various possible embodiments of my invention and of which

Figure 1 is a front elevation of the tandem chuck wind-up of this invention;

25 Figure 2 is a section on line 2—2 of Figure 1, showing the winding machine of this invention in greater detail;

Figure 3 is a section on line 3—3 of Figure 1, 30 showing the upper and lower bobbin operation in greater detail;

Figure 4 is a detail sectional plan on line 4—4 of Figure 5, showing of the brake mechanism of the lower bobbin;

35 Figure 5 is an elevation further showing the brake mechanism of the lower bobbin and

Figure 6 is a sectional detailed view of the compensating spring and set screw employed in the operation of the upper bobbin.

40 In Figures 1, 2, and 3 driving roller 1 is affixed to and rotated by shaft 2 supported on a frame and driven by a motor neither of which is shown. Driving roller 1 drives a plurality of upper bobbins 3 and a plurality of lower bobbins 4 when it is rotating and the bobbins are in surface contact with it. The upper bobbins 3 may be moved into or out of surface contact by the pivoted lever arm 5. These arms are pivoted in bearing 6 contained in upright 7 which is bolted to the frame 8. Attached at the upper end of the lever arm 5 is a brake handle 9 which is pivoted on lever arm 5 at point 10 and has a spring 11 attached to it and to arm 5. This can be seen readily in Figure 2. As soon as the bobbin 3 is

45 removed from contact with the driving roll, the

handle 9 and arm 5 are gripped manually and squeezed together. This forces the brake shoe 13 hard against the inside surface of the chuck and the rotating chuck and yarn carrying bobbin come to a stop. At the same time the bobbin is pulled into the doff position shown in Figure 2 by dotted lines 12. The bobbin can then be readily removed and replaced by a fresh bobbin. As shown in Figure 1, affixed to the lever arm 5 is a counter weight 14 which cooperates with the compensating spring 15 which is attached to the frame member 16 (see Figures 3 and 6). This spring is of the compression type and tends to push the bobbin 3 away from the drive roll. The force is exerted on set screw 17 fixed in arm 5. This screw is adjusted so that the counter-weight and the spring coact throughout the wind-up in such a manner that the pressure of the rotating bobbin on the drive roll is carefully controlled. Since a free falling bobbin, spool, chuck or core would damage the roller 1, an arresting screw 18 attached to frame member 16 is provided to stop any such bobbin before it hits the roll, thereby preventing damage.

From an examination of Figure 2 it can be seen that the upper bobbins 3 rest on drive roller 1 to some extent by force of gravity at the start of the wind-up and it moves away from roller 1 while yarn collects on it. The dotted circular line 19 shows the bobbin 3 in one position after wind-up for a given time. The dotted circular line 12 shows the bobbin in doff position. The lower bobbin 4, however, is not held against roller 1 by gravity and a somewhat different construction is preferred. Unlike the upper counter weight 14, the lower counter weight 20 is not attached directly to its corresponding lever arm, the lower bobbin pivoted arm 21. Counter-weight 20 and lower arm 21 are pivotally connected through the rod 22 and bearing 23, all being supported by the frame upright member 7. Thus, as the bobbin 4 moves away from roller 1, the arm 21 drops downward and the counter-weight 20 moves upward.

Lower compensating spring 24 is attached to arm 21 at point 25 and to the frame member 16 at point 26. As yarn builds up, the bobbin 4 moves away from the roller 1, the frictional contact being supplied by successive layers of yarn on the bobbin. The spring 24 and lower counter-weight 20 are so designed that they coact to keep the bobbin 4 throughout wind-up held against roller 1 and exerting a certain optimum pressure. A yarn carrying position of the bobbin 4 is shown by dotted line 27 and the doff position by dotted line 28. Like the upper chuck, the lower is prevented from being inadvertently allowed to fall on roller 1 by the arresting device or set screw 29 which is attached as shown to the frame member 16, as shown in Figure 2. The arrangement of lower bobbins 4 and counter-weights, etc. may also be seen in Figure 1. It is, of course, within this invention to employ other mechanical devices which are equivalent to the pivoted mountings for the wind-up cores, or to the pressure regulating, co-acting counter-weights and compensating springs, or the arresting devices, or guide mechanism or the brake mechanisms.

The rotation of the lower bobbin 4 may be stopped by operation of a brake device similar to that described above for the upper bobbin 3. However, a slightly different construction is utilized for proper spacing. The spacing must permit the ready removal and insertion of the bobbins. The figures, as, for example, Figures 1 and 2, show the position of the lower grip 30

affixed to lower pivoted arm 21. By gripping this rod 30 and pulling downward, the lower bobbin may be moved to doff position 28. Lower brake handle 31 and lower brake shoe 32 may be seen in greater detail in Figures 4 and 5.

The yarn travel may be seen most readily in Figure 2. A plurality of filamentous structures 33, such as yarns, coming from a source (not shown) such as a spinneret pass through the slot 34 of a traverse guide mechanism 35. For convenience the apparatus has been diagrammed to show how two yarns have been handled. After the two yarns have passed through the traverse guide as a single unit one thread 36 is wound up on upper bobbin 3. The other designated as 37 passes between the upper yarn cake 38 (shown in Figure 1) and the drive roller 1. It then passes around a portion of roller 1 and between the nip of roller 1 and lower bobbin 4, and is then wound on bobbin 4 to form lower cake 39. Thus, the lower thread 37 surprisingly follows the traverse guide mechanism 35 even though the thread passes through a tortuous path. It is in frictional contact at three places, first between the roller 1 and the upper yarn cake 38 then with roller 1 to bobbin 4 and again between the roller 1 and the lower yarn cake 39. In spite of this, yarn quality is not sacrificed. No noticeable difference can be detected in the physical properties of the yarn in cake 38 nor in that of cake 39 when compared to each other or to yarn wound in a conventional manner using a comparable, but single thread and a single bobbin similarly driven. Further, very high speeds can be employed to produce this high quality yarn. This is, indeed, a surprising result when one considers the pressure exerted at the points of frictional contact and the additional contact of yarn on yarn. The table below indicates the efficiency of the process:

Table.—(Nylon yarn)

	Speed, Yards/Min.	Breaks/ Pound	Brk. Fila. Ends/1,000 Yds.	Inspection Rejects for Brk. Fila., Percent
Tandem Standard ¹	1,200 967	0.51 0.56	0.08 0.10	0.95 1.10

¹ Two cakes per bobbin (twin cake process).

Thus, results equal to old process are obtained by this invention and this is true even if the yarn speeds are higher. Cost analysis indicates that a 75% reduction over standard wind-up processes and equipment may be obtained by this invention. The combination of high yarn quality and high production rate makes this invention of outstanding value.

The process and apparatus of this invention, thus, provide for exceedingly unexpected results. The winding of yarn in this manner at high speeds without snagging, breakage, wrapping on wrong bobbins, poor bobbin formation, relaxing non-uniformly, etc. is indeed surprising. As mentioned above the pressure exerted on the roller 1 by the bobbins should be carefully controlled for best results. This pressure depends, in part, upon the kind of filament being wound. For yarn, the pressure depends, among other factors, on the denier of the yarn being processed. The pressure can be as low as 500 grams and as high as 5000 grams. For example, for 20 denier polyamide yarn it is preferred to adjust the coacting counter weights and compensating springs so that a pressure of 1700 ± 100 grams

is exerted on a 5 inch linear surface. If too high a pressure is used the packages flatten out and lose their formation. If too low a pressure is used, the package may run slowly causing yarn breaks to occur on the feed roll, or a build-up of soft yarn package that flattens out may occur resulting again in poor formation. While pressures higher and lower than those indicated may be employed, it is preferred for most purposes to use pressures between about 100 grams and 1000 per inch of linear surface.

As indicated in the table excellent results are obtained in this invention using a yarn speed of 1200 yds. per min. The invention is not limited in this respect and lower or higher speeds may be employed. In fact, the tandem chuck wind-up of this invention may be used at any speed where a standard free driven bobbin can be used.

Nor is the invention limited to the type of filament being wound. The yarns may be those prepared from natural materials such as wool, cotton or silk or they may be synthetic materials prepared from cellulose derivatives, such as cellulose acetate or from other polymeric materials including viscose, acrylonitrile polymers, polyamides, polyesters, polyester-amides, or vinyl polymers such as vinyl chloride polymers. Likewise filaments from inorganic materials, such as metallic wires may be wound on the apparatus of this invention. The filaments processed may vary widely in size. For example, nylon yarns from 66 to 1000 denier (undrawn yarn) have been wound successfully by the process of this invention. The process and apparatus of this invention may, of course, be used in connection with drawing processes and machines. The various parts of the apparatus may be made of any appropriate material, such as metals, alloys, plastic, glass, enamels, etc.

The apparatus may be adapted to process more than two filamentous structures simultaneously. For example, for each position two additional bobbins can be run, one upper bobbin positioned opposite bobbin 3 and another lower bobbin opposite bobbin 4. Further, the diameter of the driving roller can be greatly increased to accommodate one or more bobbins between upper bobbin 3 and lower bobbin 4. Also the length of the drive roller may be very large. The process and apparatus of this invention thereby provide means for greatly increasing plant capacity. The wind-up capacity is doubled per unit length of drive roll when using two bobbins in tandem, is tripled when using 3 bobbins in tandem, etc. For example, machines are usually designed so that there is one wind-up bobbin for each spinneret. A specific denier must be produced although the spinneret is capable of producing light or heavy deniers. In comparing the standard method of spinning one end of 40 denier and winding to one bobbin as against spinning 80 denier, splitting to two ends of 40 denier, and winding each end to a separate bobbin of two in tandem, the output per position is doubled. Thus, there results an outstanding advantageous economy in space, equipment and time.

The above description has shown the operation of this invention using a single traverse guide. While the use of only one traverse guide is highly desirable in the interests of space and equipment, it is possible and occasionally desirable to employ as the guide mechanism a plurality of traverse guides. For example, two traverse guides may be used, one in front of the

other. Further, two traverse guides may be used one along side of the other and fastened to the same traverse bar. In winding bobbins from warps using this latter arrangement, a desirable uniform displacement of threads across the roll surface occurs. To illustrate, each of 10 ends spaced 0.5 inch apart from a warp 4.5 inches wide are passed individually through a traverse guide, the 10 guides being on the same traverse bar and spaced 0.5 inch apart. Ten wind-up bobbins are placed one behind the other with their center lines offset 0.5 inch from the leading bobbins, thereby accomplishing the desired displacement. Still further if two sets of threads are to be wound on opposite sides of the same bobbin drive roll, the use of a second traverse bar and a second guide is desirable.

For example, a yarn comprising four filaments A, B, C, and D can be passed through the slot 34 of thread guide 35. Thread A may be passed to bobbin 3 in a manner similar to yarn 36. Thread B may be wound on bobbin 4 like yarn 37. Similarly threads C and D may be passed to bobbins located opposite to bobbins 3 and 4, respectively. Two thread guides may be used if desired.

The process and apparatus of this invention may also be used to break up a plurality of filamentous structures into smaller pluralities. For example, a structure comprising 150 filaments may be wound so that 75 of the filaments are wound on the top bobbin 3 and the remainder on the bottom bobbin 4. Packages so produced are useful in further operations, either in further separations or in recombinations to form strands, cords, etc. It is also possible to form more than one cake on a bobbin. For example, a total of six unit filamentous structures of 66 denier each is fed to the apparatus so that two unit structures go to each of three guide mechanisms situated above the upper bobbin 3 and a sufficient distance apart to allow for a convenient space between the cakes. Three cakes are formed on the upper bobbin 3 from a unit structure passing thru each of the three guides and the remaining 3 unit structures pass in the usual manner to lower bobbin 4 and are wound thereon to form three individual cakes. The apparatus and process of this invention permit a large variety of wind-ups.

Any departure from the above description which conforms to the present invention is intended to be included within the scope of the claims.

I claim:

1. A process for winding filamentous structures which comprises surface driving a core on an upper section of a rotating drive roll; surface driving a second core on a lower section of said rotating drive roll; passing a plurality of said structures through a guide mechanism and then through the nip formed by the said upper wind-up core and said drive roll; separating a portion of said structures from said plurality; passing this portion to said upper core and winding it thereon; passing the remainder of said plurality through the nip formed by said lower wind-up core and said drive roll; and winding said remainder on said lower core.

2. A process for winding filamentous structures which comprises rotating an upper wind-up core on an upper section of a rotating drive roll; rotating a lower wind-up core on a lower section of said drive roll; passing a plurality of said structures through a guide mechanism and then through the nip formed by said upper core

and said drive roll; separating a portion of said plurality; passing this portion to said upper core and winding it thereon; passing the remainder of said plurality through the nip formed by said lower core and said drive roll; separating a second portion of said plurality; passing this second portion to said lower core and winding it thereon; and repeating the process until the final portion of said plurality is wound separately on a core.

3. A process in accordance with claim 2 in 10 which the pressure exerted on the said drive roll between the said wind-up cores is controlled.

4. Apparatus for separating and winding on individual cores filamentous structures travelling in a group which comprises a traversing guide; a drive roll having a smooth surface; an upper wind-up core surface-driven on an upper section of said drive roll to receive a portion of said structures; a lower wind-up core surface-driven on a lower section of said drive roll to receive another portion of said structures; and a guide comprising a section of said smooth surface on said drive roll, said section being exposed between said upper and said lower wind-up cores to contact the portion of said structure that by-passes one of said cores in its travel to the other of said cores.

5. A plurality of the apparatus in accordance with claim 4 arranged in tier fashion.

6. Apparatus in accordance with claim 4 containing pressure regulating devices for said upper core and for said lower core.

7. Apparatus for separating and winding on individual cores a plurality of filamentous structures which comprises, in combination, a drive roll having a smooth surface; an upper wind-up core surface-driven on an upper section of said roll to receive a portion of said structures; in a lower position in respect to said upper core, a lower wind-up core surface-driven on a lower section of said roll to receive another portion of said structures; a guide for simultaneously traversing a portion of said plurality of said structures on said upper core and a portion of said plurality of said structures on said lower core as each portion is wound on its respective core; and a guide comprising a section of said smooth surface on said drive roll, said section being exposed between said upper and said lower wind-up cores to contact the portion of said structure that by-passes one of said cores in its travel to the other of said cores.

8. Apparatus for separating and winding on individual cores a plurality of filamentous structures which comprises, in combination, a drive roll having a smooth surface; an upper wind-up core surface-driven on an upper section of said roll to receive a portion of said structures; in a lower position in respect to said upper core, a lower wind-up core surface-driven on a lower section of said roll to receive another portion of said structures; pressure regulating devices for said upper core and for said lower core; a guide for simultaneously traversing a portion of said plurality of said structures on said upper core and a portion of said plurality of said structures on said lower core as each portion is wound on its respective core; and a guide comprising a sec-

tion of said smooth surface on said drive roll, said section being between said upper and said lower wind-up cores and being exposed to contact the portion of said structure that by-passes one of said cores in its travel to the other of said cores.

9. Apparatus for separating and winding on individual cores a plurality of filamentous structures which comprises, in combination, a drive roll having a smooth surface; an upper wind-up core surface-driven on an upper section of said roll to receive a portion of said structures; in a lower position in respect to said upper core a lower wind-up core surface-driven on a lower section of said roll to receive another portion of said structures; counter-weights and compensating springs for said upper core and for said lower core; pivoted mountings for said upper core and for said lower core; a guide for simultaneously traversing a portion of said plurality of said structures on said upper core and a portion of said plurality of said structures on said lower core as each portion is wound on its respective core; and a guide comprising a section of said smooth surface on said drive roll, said section being exposed between said upper and said lower wind-up cores to contact the portion of said structures that by-passes one of said cores in its travel to the other of said cores.

10. Apparatus for separating and winding on individual cores a plurality of filamentous structures which comprises, in combination, a drive roll having a smooth surface; an upper wind-up core surface-driven on an upper section of said roll to receive a portion of said structures; in a lower position in respect to said upper core a lower wind-up core surface-driven on a lower section of said roll to receive another portion of said structures; counter-weights and compensating springs for said upper core and for said lower core; pivoted mountings for said upper core and for said lower core; arresting devices for said upper and said lower cores; a guide for simultaneously traversing a portion of said plurality of said structures on said upper core and a portion of said structure on said lower core as each portion is wound on its respective core; and a guide comprising a section of said smooth surface on said drive roll, said section being exposed between said upper and said lower wind-up cores to contact the portion of said structures that by-passes one of said cores in its travel to the other of said cores.
